UNITED STATES PATENT OFFICE.

MEYER I. GERSON, OF NEW YORK, N. Y., ASSIGNOR TO UNION TAXI OWNERS ASSOCIATION, OF NEW YORK, N. Y., A COPARTNERSHIP COMPOSED OF LOUIS ALPERT, HARRY EISENBERG, AND JACK BLUESTEIN, ALL OF NEW YORK, N. Y.

DESIGN FOR A BADGE.

Application filed December 8, 1926. Serial No. 19,963. Term of patent $3\frac{1}{2}$ years.

To all whom it may concern:

Be it known that I, MEYER I. GERSON, a citizen of the United States, and a resident of New York city, borough of Manhattan, in the county and State of New York, have invented a new, original, and ornamental Design for a Badge, of which the following is a specification, reference being had to the accompanying drawing, forming part thereof.

Fig. 1 is a view in front elevation of a badge showing my new design.

Fig. 2 is a top plan view thereof.

I claim:

The ornamental design for a badge substantially as shown.

MEYER I. GERSON.
